(57) **CLAIM**

We claim the ornamental design for a sheath for syringe needle, as shown and described.

DESCRIPTION

FIG. 1 is a front perspective view of a sheath for syringe needle, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view thereof, taken along the line 8-8 in FIG. 4; and,

FIG. 9 is an enlarged cross-sectional view thereof, taken along the line 9-9 in FIG. 4.

Portions of the claimed design shown in broken lines form no part of the claimed design.
